UNITED STATES PATENT OFFICE.

HERBERT N. ROCHE AND FRED F. BREESE, OF SAN FRANCISCO, CALIFORNIA,
ASSIGNORS OF ONE-HALF TO THE JAMES W. EDWARDS CO., ONE-FOURTH
TO SAID HERBERT N. ROCHE, AND ONE-FOURTH TO THOMAS B. GRAY,
OF SAN FRANCISCO, CALIFORNIA.

INSTANTANEOUS ELECTRIC WATER-HEATER.

No. 858,351.

Specification of Letters Patent.

Patented June 25, 1907.

Application filed October 20, 1904. Serial No. 229,227.

To all whom it may concern:

Be it known that we, HERBERT N. ROCHE and FRED F. BREESE, citizens of the United States, residing at San Francisco, in the county of San Francisco and State of California, have invented certain new and useful Improvements in Instantaneous Electric Water-Heaters, of which the following is a specification.

This invention relates to instantaneous electric water heaters, the object of our invention being to provide a device of this character which shall be compact in form, simple in construction, capable of easy inspection and repair, and which can be operated to deliver water without using the heating apparatus, that is, to deliver cold water when desired, and especially to provide a construction which will render it impossible to turn on the electric current without at the same time turning on the water.

In the accompanying drawing, Figure 1 is a broken side elevation of the apparatus; Fig. 2 is a broken side view of a heater; Fig. 3 is an enlarged broken horizontal section on the line 3—3 of Fig. 1; Fig. 4 is a similar view on the line 4—4 of Fig. 1. Fig. 5 is a broken side view of the lower part of the apparatus at right angles to Fig. 1.

Referring to the drawing, 1 represents the inlet branch pipe of a valve casing 2, in which is the valve 3 operated by a handle 4, said valve turning through a right angle in either direction from the position shutting off the water to that turning it on in full. An uplift pipe 5 leading from said valve casing passes through the bottom of a cylindrical casing 6, which incloses a number of heating tubes 7, of which in the present instance we have shown three, although the number may be varied. The bottom of each heating tube is permanently closed except for an opening 8 at one side thereof. Said tubes are so arranged that all of said openings 8 are located as near as possible to the central axis of the casing, and all of these openings are covered by a cover 9 which has centrally secured thereto a pipe 10 which is screwed into the end of the uplift pipe 5. Hence the water can pass from said pipe 5 through said openings into the interior of

said heating tubes. The space between the tubes 7 at the bottom is filled with solder 44. The inner surface of each heating tube is lined with insulating material 11, as, for instance, vulcanized fiber, and within the same is inserted a heater comprising, first, a tube 12 of porcelain or other suitable non-conducting material, secondly, a high resistance wire 13 which is first formed into a cylindrical coil and inserted into the porcelain tube, is then passed around the bottom of the tube to the outside of the same and is then wound in a spiral coil up to the upper end of the tube, and thirdly, a round rod 14 of porcelain, slate, or other non-conducting material, not affecting, or being affected by, water. The object of this rod is to fill up the space inside the inner coil, compelling the water to flow rapidly, but in a small stream, over the high resistance wire, and for this same object the porcelain tube is made of such diameter that when the high resistance wire is wrapped around the same, it almost fills the heating tube. To obtain the best results the volume of water in each heating tube should be as small as possible for a given quantity of heating surface of wire, this small volume being compensated by a rapid flow.

The ends of the coils in each heating tube are connected to diametrically opposite terminals 15 in the form of screws screwed through hard rubber sleeves 16 which are again screwed through bearings 17 secured to the sides of the tube. By this means the electric circuit is continued to the outside of the tube, while being insulated therefrom, and providing no chance for leakage of the water. The tops of the tubes are closed by caps 18 which are screwed into the tubes by slots 40, and said caps have small openings 19 near the side of the cap, said openings being all brought as near as possible to the central axis between the three tubes, and they are then inclosed by a cover 20 soldered down upon the caps, said cover having a pipe 21 extending upward from the middle thereof and passing through the cover 22 for the casing, said cover being secured to said casing by screws 23. A discharge pipe 24 is passed through a central hole in said cover, into the

lower end of which discharge pipe the upper end of the tube 21 passes, and said lower end is screwed down upon said tube.

The wires from the several coils are connected, preferably in parallel, with terminals 26 which extend through an opening 27 cut in the side of the casing, and pass through and are supported by an insulating block 28 which is screwed on to said casing and closes said opening. These terminals on the outside of said block are apertured vertically as shown at 29 and through said vertical apertures slide metallic bars 30 connected to an insulating block 31 secured upon the end of a rod 32 sliding through a bearing 33 secured upon the outside of the casing, the lower end of said rod having secured thereto a rack 34 which slides in a slideway 35 and meshes with a gear wheel 36 secured to the stem of the valve 3, said slideway being attached to a bracket 42 secured to the bottom of the casing. The upper end of said metallic rods 30 are adapted to slide into and through vertical holes 37 formed in terminals 38 secured to an insulating block 39 secured upon the top of the cover 22 of the casing, and to said terminal 38 are secured wires 41 connected with a suitable electric circuit. The arrangement is such that the valve 3 is opened before said slide bars come into contact with said upper terminals 38, so that there is no circuit until after the water has commenced flowing. This prevents overheating of the wires and consequent injury to the apparatus. To obtain cold water the valve is turned in the opposite direction through a right angle, which opens the valve without closing the circuit.

It will be observed that the openings 8 at the bottom of the heating tubes are considerably larger than the openings 19 at the top thereof; this avoids any diminution of pressure in the heater.

We claim:—

1. In an apparatus of the character described, the combination of a casing, a plurality of heating tubes therein, a lining or insulating material on the inside of each tube, a tube of non-conducting material within each tube, a coil of high resistance wire within the inner tube, said wire being continued in a coil on the outside of the tube, a rod of non-conducting material within the inner coil, means for connecting the ends of the coils of the sev-

eral tubes in series, means for connecting the ends of the series thus formed with an electric circuit, means for admitting water in succession through the outer tubes, and an operative connection between said means whereby they act in unison, substantially as described.

2. In an apparatus of the character described, the combination of a casing, a water conduit therein, an electric heating coil in the water conduit, terminals on the casing connected to the ends of said coils, a second pair of terminals on the casing connected with an electric circuit, a valve supplying water to the water conduit, and a pair of slide bars sliding through the one pair of terminals and operatively connected with the valve to contact with the other terminals respectively when the valve is open, substantially as described.

3. In an apparatus of the character described, the combination of a casing, a plurality of parallel heating tubes therein each having an end closed except for a small opening therein, all of the openings being arranged near to each other, a cover inclosing all of said openings, a pipe leading therefrom, electric heaters in the several tubes, means for supplying water to the tubes, and means for supplying electricity to the heaters, substantially as described.

4. In an apparatus of the character described, the combination of a casing, a plurality of parallel heating tubes therein, each tube having a large opening in its supply end and a small opening in its discharge end, all the openings at each end being arranged near to each other, a cover inclosing the openings at each end, means for supplying water to the cover at the supply end and discharging it from the cover at the discharge end, electric heaters in the several tubes, and means for supplying electricity to the same, substantially as described.

In witness whereof we have hereunto set our hands in the presence of two subscribing witnesses.

HERBERT N. ROCHE.
